UNITED STATES PATENT OFFICE.

AXEL G. J. RAPP, OF CHICAGO, ILLINOIS, ASSIGNOR TO LINK-BELT COMPANY, OF CHICAGO, ILLINOIS, A CORPORATION OF ILLINOIS.

SUGAR-BEET-CLEANING SCREEN.

Application filed December 15, 1921. Serial No. 522,638.

To all whom it may concern:

Be it known that I, AXEL G. J. RAPP, a citizen of the United States, residing at Chicago, in the county of Cook and State of Illinois, have invented a certain new and useful Improvement in Sugar-Beet-Cleaning Screens, of which the following is a specification.

My invention relates to improvements in sugar beet cleaning screens, and has for one object to provide a new and improved form of screen which will be easy, simple and cheap to construct, and wherein those parts likely to need replacement can be easily and quickly renewed without dismantling the machine and without materially interfering with its operation.

Another object is to provide a sugar beet cleaning screen which will be self-cleaning and which will remove dirt from beets with maximum efficiency.

Other objects of my invention will appear from time to time throughout the course of the specifications and claims.

By my arrangement I provide a screening drum made of a series of separate loosely held transverse cleaning bars. The fact that these bars are loosely held and free to rattle about slightly in the frame avoids the tendency for dirt to cake between the bars and enables the bars themselves to shake caked dirt loose.

The arrangement is such that if a bar is bent or broken, it is only necessary to insert a new bar into the holes occupied by the old one and to bend the ends to hold the bar in place, or the bar with bent ends can be sprung into place.

The spaces between the bars extending in the direction of movement of the beets or other material being separated as it travels along the rotating screen provide for a free and smooth travel of material as it continually rotates and makes it possible for the beets themselves to assist in cleaning the screen.

My invention is illustrated more or less diagrammatically in the following drawings, wherein:

Figure 1 is a side elevation of the screen;

Figure 2 is a view of the receiving end with the supply chute removed;

Figure 3 is a view of the discharge end with the discharge chute removed;

Figure 4 is a section along the line 4—4 of Figure 1;

Figure 5 is a detail section along the line 5—5 of Figure 1;

Figure 6 is a detail section along the line 6—6 of Figure 1.

Like parts are indicated by like characters throughout.

A is a main bed frame, carrying pillow blocks A', A', in which are rotatably mounted the roller shafts A², A². These shafts have on their ends mitre gears A³ in mesh with mitre gears A⁴ on the driving shaft A⁵, which is driven from any suitable source of power by a drive pulley A⁶. A⁷, A⁷ are supporting rollers on the roller shafts A², A², in frictional engagement with the supporting rings A⁸, A⁹, whereby power applied to the machine itself causes the supporting rings and screen to rotate by the frictional engagement between the rollers A⁷ and rings A⁸.

Rings A⁸, A⁹, have inwardly extending lugs B, on which are bolted the longitudinally disposed T bars B', B', parallel with the axis of rotation of the screen. The two inner flanges of these T bars have each longitudinally disposed rows of perforations B², B². Screen bars B³, B³, engage these perforations, the ends of the bars being bent outwardly as at B⁴, B⁴, roughly into parallelism with the stem of the T, so that these bars, which are smaller in diameter than the holes B', are held at their ends in those holes loosely, but are unable to escape from them. In the preferred form as shown, these bars are slightly inclined so as to give a spiral arrangement of the bars about the periphery of the drum, but obviously this inclination might vary in degree, and under some conditions the bars might preferably be perpendicular to the axis of rotation. The bent ends of these bars penetrate through the T flanges so as to provide little, if any, obstruction for the free flow of the material down one bank of bars, across the base of the T and on to the next bank or row of bars. B⁵ are filler plates bolted to the lugs B in the same plane as the bars, so as to continue the support of

the bars.

beets until they are discharged from the drum on to the discharge sleeve B^6 , mounted on the ring A^9 . B^7 is a chute into which the beets are discharged from the sleeve B^6 . B^8 is a feed chute through which the dirty beets are discharged into the screen. B^9 is an inwardly extending annular guard ring mounted on the ring A^8 and engaging the edges of the members B^5 on the up side so as 10 to protect the operating mechanism.

The screening drum is slightly inclined as indicated and limited in its downward movement by a roller C , which is mounted on the frame A and engages the down side 15 of the ring A^9 . The operation of the device will be obvious at a glance. The dirt-laden beets, which must be separated from dirt before shipment, or treatment, are fed into the drum and as the drum rotates, the beets 20 travel down on to the slight incline of the drum and to the spiral arrangement of the bars. The polygonal cross section of the drum causes the beets to roll upon one another and to change direction with some 25 suddenness and dirt and foreign material is discharged from between the bars into any suitable chute or hopper, C' , hence the material carried off in any desirable way, and the cleaned or separated beets are discharged 30 into the discharge hopper.

It will be evident that while I have shown in my drawings an operative device, still many changes might be made in size, shape and arrangement of parts without departing materially from the spirit of my invention and I wish, therefore, that my drawings be considered as in a sense diagrammatic.

I claim:

1. A rotary screen comprising a supporting frame and a plurality of separate loosely mounted screening elements supported at each end thereon.

2. A rotary screen comprising a supporting frame and a plurality of separate screen-forming elements, each loosely mounted on the frame and supported at each end thereon.

3. A rotary screen comprising a supporting frame and a plurality of screening bars, each separately loosely mounted in the 50 frame and supported at each end thereon.

4. A rotary screen comprising two parallel perforated supporting members and separate screen-forming bars extending between said supporting members, having 55 their ends penetrating said perforations.

5. A rotary screen comprising two parallel perforated supporting members, and separate screen-forming bars extending between said supporting members, having 60 their ends penetrating said perforations, the ends of the bars being bent to prevent removal thereof.

6. A rotary screen comprising two parallel perforated supporting members and

separate screen-forming bars extending between said supporting members, having their ends penetrating said perforations, the ends of the bars being bent at the point where they penetrate said perforations to prevent removal thereof.

7. A rotary screen comprising a supporting frame and a plurality of separate loosely mounted screening elements carried thereby, and supported at each end thereon and means for moving the supporting frame 75 during the screening operation to rattle said loosely mounted members to prevent clogging of the screen.

8. A rotary screen comprising a supporting frame and a plurality of separate screen-forming elements, each loosely mounted at each end on the frame, and means for moving the supporting frame during the screening operation to rattle said loosely mounted members to prevent clogging of the screen.

9. A rotary screen comprising a supporting frame and a plurality of screening bars each separate from the others and separately and loosely mounted in the frame, and means for moving the supporting frame 90 during the screening operation.

10. A tubular screen, the side walls of which are made up of a plurality of plane panels inclined one to the other each panel comprising a plurality of loosely mounted 95 elements.

11. A tubular screen, the side walls of which are made up of a plurality of plane panels inclined one to the other each panel comprising a plurality of loosely mounted 100 elements, there being a series of longitudinal screening apertures in each of said panels located in planes normal to and intersecting the axis of rotation of the screen.

12. A tubular screen, the side walls of 105 which are made up of a plurality of plane panels inclined one to the other each panel comprising a plurality of loosely mounted elements, there being a series of longitudinal screening apertures in said panels located in planes generally parallel with the movement of material across the screen as the screen rotates.

13. In a tubular screen a plurality of plane panels comprising separate loosely 115 mounted screen-forming elements generally normal to the axis of rotation.

14. In a tubular screen a plurality of plane panels comprising loosely mounted screen-forming rods generally normal to the 120 axis of rotation.

15. In a tubular screen a plurality of plane panels comprising separate screen-forming rods generally normal to the axis of rotation, each of said rods being loosely 125 mounted and free to move during the screening operation, with respect to its neighbor under the impact of material being screened,

and as a result of rotation of the screen to prevent the deposition of clogging material between the rods.

16. A rotary screen comprising a plurality of annular supporting rings, a plurality of longitudinal members joining them, a plurality of separate screening bars loosely mounted at their ends on said members to form screen panels between them.

10 17. A rotary screen comprising a plurality of annular supporting rings, a plurality of longitudinal members joining them, a plurality of separate screening bars loosely mounted at their ends on said members to form screen panels between them, the rods being slightly inclined to form a series of spiral slots about the periphery of the screen cylinder.

18. A rotary screen comprising a plurality of annular supporting rings, a plurality of longitudinal members joining them, a plurality of separate screening bars loosely mounted at their ends on said members to form screen panels between them, the longitudinal members being perforated, the screening bars loosely held within said perforations.

19. A rotary screen comprising a plurality of annular supporting rings, a plurality of longitudinal members joining them, a plurality of separate screening bars loosely mounted at their ends on said members to form screen panels between them, the longitudinal members being perforated, the screening bars loosely held within said perforations, the ends of the bars where they pass through said apertures being outwardly bent.

20. A screen comprising a plurality of annular supporting rings, a plurality of longitudinal members joining them, a plurality of separate screening bars loosely mounted at their ends on said members to form screen panels between them, the longitudinal members being perforated, the screening bars loosely held within said perforations, there being a smooth surface of the longitudinal members between the ends of the bars forming adjacent screen banks.

21. A screen comprising a plurality of annular supporting rings, a plurality of longitudinal members joining them, a plurality of separate screening bars loosely mounted at their ends on said members to form screen panels between them, the longitudinal members being perforated, the screening bars loosely held within said perforations, the ends of the bars where they pass through

said perforations being outwardly bent, there being a smooth surface of the longitudinal members between the ends of the bars forming adjacent screen banks.

22. A screen comprising a plurality of annular supporting rings, a plurality of longitudinal T-shaped members joining them, the stem of the T projecting outwardly, a plurality of separate screening bars loosely mounted at their ends on said members to form screen panels between them.

23. A screen comprising a plurality of annular supporting rings, a plurality of longitudinal T-shaped members joining them, the stem of the T projecting outwardly, the flanges of the T being perforated, the ends of the screening bars passing through the perforations and bent outwardly along the stem of the T.

24. A screen comprising a plurality of annular supporting rings having opposed inwardly projecting lugs longitudinal members attached to said lugs and connecting the rings, screening bars loosely mounted at their ends on the longitudinal members and forming screen banks between them and flat reinforcing plates connecting adjacent lugs on each annular ring in continuation of the screen banks.

25. A screen comprising a supporting frame and means for passing material thereacross, and a plurality of screening bars, each separately and loosely mounted in the frame, said bars lying across the line of movement of the material to be screened.

26. A screen comprising a supporting frame and means for passing material thereacross, and a plurality of screening bars, each separately and loosely mounted in the frame, said frame comprising parallel perforated supporting elements, said screening bars having their ends penetrating said perforations, said bars lying across the line of travel of the material to be screened.

27. A screen comprising a supporting frame and means for passing material thereacross, and a plurality of screening bars, each separately and loosely mounted in the frame, said screening bars having their ends penetrating said perforations, said ends being bent at the point where they penetrate to prevent removal thereof, said bars lying across the line of travel of the material to be screened.

Signed at Chicago, county of Cook, and State of Illinois, this 12th day of December, 1921.

AXEL G. J. RAPP.
